UNITED STATES PATENT OFFICE.

JOHN HEPWORTH, OF MONTREAL, QUEBEC, CANADA.

VARIABLE EXPANSION-GEAR.

SPECIFICATION forming part of Letters Patent No. 363,825, dated May 31, 1887.

Application filed February 10, 1887. Serial No. 227,148. (No model.) Patented in Canada February 14, 1887, No. 25,998.

To all whom it may concern:

Be it known that I, JOHN HEPWORTH, of the city of Montreal, in the district of Montreal and Province of Quebec, Canada, have invented certain new and useful Improvements in Variable Expansion-Gears; and I do hereby declare that the following is a full, clear, and exact description of the same.

The object of my invention is to provide an instantaneouse cut-off applicable to engines using a D slide-valve, the point of cut-off being automatically regulated by the connection of the operating parts with the governor, the main-valve stem being, as usual, actuated by the eccentric.

The invention may be thus briefly described: Upon the main-valve stem is formed a flat downward extension, on the lower edge of which is a step or projection, and on the face of this extension is pivoted, in its center, a four-armed piece, the upper end of which is connected by a pivot-pin with the riding-valve stem, and the opposite end has attached to it the free ends of two springs secured to fixed parts of the engine, and so arranged that when the cut-off and main valves are in a central position the tension on both springs will be equal. To a bracket or standard, serving as the valve-spindle guide secured to the engine, is pivoted a double crank, to which are pivoted links connected with the ends of tripping-levers, also pivoted to the bracket. To the cross-arms of the four-armed piece are pivoted stops which are so adjusted that one stop will engage with the step at the foot of the plate to which the four-armed piece is pivoted, until, when the cut-off valve has closed one or the other of the steam-passages of the main valve, the movement of the main-valve stem will bring the stop in contact with one of the tripping-levers, thus disengaging it and thereby freeing the spring which has been in tension, and which will draw the lower end of the four-armed piece in the opposite direction, throwing over the cut-off valve and instantaneously closing the passage which had been open before and opening that which had been shut.

For full comprehension, however, of the invention, reference must be had to the annexed drawings, forming part of this specification, in which—

Figure 1 is a longitudinal vertical sectional

elevation through the cylinder and steam-chest of a stationary engine embodying my invention; Fig. 2, an end view of mechanism actuating cut-off, enlarged; Fig. 3, a detail of four-armed piece in perspective; and Fig. 4, a detail, also in perspective, of standard or valve-stem guide to which the double-crank lever is pivoted.

Similar letters of reference indicate like parts.

The cylinder, steam-chest and steam-passages, piston, piston-rod, and main-valve action being of any approved construction, no further particular allusion will be made to them.

A is a standard or bracket, bolted in this case to the upper slide-bar of cross-head, as shown in Fig. 1, to which is pivoted at *a* the double-crank lever B, the extended end *b* of this being connected by a stud and rod, *b'*, and bell-crank lever *b''*, or other suitable means, with the governor B'.

C' are tripping-levers pivoted to the standard A, and connected by links C² C³ to the double crank B, *c c'* being studs carried on the ends of these levers.

D is the main valve stem, D' an extension formed on same, and D² a step or projection formed on the lower end of such extension.

E is the cross or four-armed piece, pivoted at *e* to D', and carrying on the ends of its side arms stops F F', pivoted to them. The end of the upper arm is pivoted to the stem G of the riding-valve H, and to the end of the lower arm are attached the ends of two springs, J J', having their other ends connected to fixed points.

The valve H is usually, as shown in Fig. 1, formed with an intermediate throat-piece, *h*, corresponding with a similar piece in the passage of the main valve, and upon the ends of the main valve are formed seats K K, between which and the ends of the valve H are spaces K' K', in which the steam will form a cushion, so as to prevent too sharp an impact of the valve when drawn over.

The operation of my invention is as follows: The parts are, as shown in Figs. 1, 2, and 3, in the several positions they assume when the piston is at the beginning of its back-stroke, the main valve traveling in the same direction as the piston. So soon as (in this case) the stop

F, carried in the side arm of the four-armed piece E, comes in contact with the stud e, it is knocked off the step or projection D², thereby releasing the four-armed lever E, and allowing the spring J', which has been in tension, to draw over the end of the lever E, to which it is attached, and instantaneously reverse the position of the riding or cut-off valve, thereby cutting off the steam from the port in the valve which had previously been open, and opening that which had been closed. It will be seen that at the time of cut-off the riding-valve has no pressure, as it is *in equilibrio* with the steam underneath.

15 The action of the governor in regulating the speed serves to bring together or widen apart the ends of the tripping-levers C C', according as the speed at which the engine is traveling increases or diminishes.

20 Concussion from the impact of the cut-off valve H against the main valve is prevented by the steam in the recesses K' K' forming cushions to receive it.

It must be understood that although I have 25 in this description and the drawings hereto annexed shown and described my invention as applied to a D-valve, it is equally applicable to every kind of slide or piston valves.

Having thus described my invention, I beg 30 to state that what I claim is as follows:

1. In a steam-engine, the combination of the following elements, viz: a downward exten-

sion on main-valve stem, a lever pivoted to such extension and having its upper end pivoted to stem of riding-valve and lower end 35 connected by tension-springs with fixed points on the engine, and means for holding such lever and releasing it by action of main-valve stem, all substantially as herein described, and for the purposes set forth.

2. In a steam-engine, the combination of the following elements: a bracket or standard secured to engine, a double crank pivoted to same and connected with governor of engine, a four-armed or cross piece pivoted to downward extension of main-valve stem, stops pivoted to cross-arms of such four-armed piece and engaging with step of downward extension, and tripping-levers pivoted to standard and connected by links with double crank, all 40 45 50 as herein set forth.

3. The combination, in a steam-engine, of the main-valve stem D and extension D' with step D², four-armed piece E, pivoted to D' and to stem G, springs J J', pivoted to its lower end, and stops F F' to its side arms, double-crank lever B, and tripping-levers C C', pivoted to bracket A, and link C² C³, connecting said levers with crank, all as herein described, and for the purposes set forth.

JOHN HEPWORTH.
